UNITED STATES PATENT OFFICE

125,857

DESIGN FOR A HEIGHT INDICATING RULE SLIDE

Samuel George Zuckerman, Brooklyn, N. Y.

Application December 19, 1940, Serial No. 97,468

Term of patent 14 years

To all whom it may concern:

Be it known that I, Samuel George Zuckerman, a citizen of the United States, resident of Brooklyn, in the county of Kings, city and State of New York, have invented a new, original, and ornamental Design for a Height Indicating Rule Slide, of which the following is a specification, reference being had to the accompanying drawing, forming part thereof.

Fig. 1 is a front view of the height indicating rule slide, showing my new design, a fragmentary portion of a rule being illustrated in dotted lines; and

Fig. 2 is a top plan view thereof.

The essential features of my design reside in the portions illustrated in full lines in the drawing.

I claim:

The ornamental design for a height indicating rule slide, substantially as shown and described.

SAMUEL GEORGE ZUCKERMAN.
